UNITED STATES PATENT OFFICE.

WILSON R. WOODS, OF LOS ANGELES, AND JAMES F. LANGSTON, OF LANCASTER,
CALIFORNIA.

DESIGN FOR A FRAME FOR A MEAT-CUTTING MACHINE.

59,315.

Specification for Design.

Patented Oct. 4, 1921.

Application filed February 9, 1920. Serial No. 357,363. Term of patent 14 years.

To all whom it may concern:

Be it known that we, WILSON R. Woods and JAMES F. LANGSTON, citizens of the United States, residing at Los Angeles and Lancaster, respectively, in the county of Los Angeles, State of California, have invented a new, original, and ornamental Design for a Frame for a Meat-Cutting Machine, of which the following is a specification, reference being had to the accompanying drawing, forming part thereof.

The figure is a perspective view of a meat cutting machine, showing our new design.

We claim:

The ornamental design for a frame for a meat cutting machine, as shown.

WILSON R. WOODS.
JAMES F. LANGSTON.
